(57) **CLAIM**

The ornamental design for an operating section for body composition meter, as shown and described.

DESCRIPTION

FIG. 1 is a perspective view of an operating section for body composition meter according to my novel design;

FIG. 2 is a front view of the operating section for body composition meter of FIG. 1;

FIG. 3 is a rear view of the operating section for body composition meter of FIG. 1;

FIG. 4 is a left side view of the operating section for body composition meter of FIG. 1;

FIG. 5 is a right side view of the operating section for body composition meter of FIG. 1;

FIG. 6 is a plan view of the operating section for body composition meter of FIG. 1;

FIG. 7 is a bottom view of the operating section for body composition meter of FIG. 1;

FIG. 8 is an enlarged view of the operating section as indicated by solid line in FIG. 6;

FIG. 9 is a plan view of the operating section for body composition meter in FIG. 6 with the display being switched on.

FIG. 10 is a plan view of the operating section for body composition meter in FIG. 6 with English legend being put on the top surface of the operating keys;

FIG. 11 is an enlarged view of the operating section in FIG. 8 with English legend being put on the top surface of the operating keys; and,

FIG. 12 is a plan view of the operating section for body composition meter in FIG. 9 with English legend being put on the top surface of the operating keys.

The broken line in FIGS. 1 to 12 showing a representative shape of the body composition meter, is for illustrative purpose only, and forms no part of the claimed design.
